UNITED STATES PATENT OFFICE.

MAUD R. HARTZ, OF RICHMOND, VIRGINIA.

WOVEN FABRIC.

SPECIFICATION forming part of Letters Patent No. 645,318, dated March 13, 1900.

Application filed April 25, 1899. Serial No. 714,437. (No specimens.)

To all whom it may concern:

Be it known that I, MAUD R. HARTZ, of Richmond, in the county of Henrico and State of Virginia, have invented a new and Improved 5 Woven Fabric, of which the following is a full, clear, and exact description.

The invention relates to fabrics particularly adapted for linings; and the object is to provide a fabric comprising bristles arranged 10 in such manner as to provide a varying degree of flexibility transversely of the fabric, whereby the article lined with the fabric will have varying degrees of flexibility.

I will describe a fabric embodying my in- 15 vention and then point out the novel features in the appended claim.

Reference is to be had to the accompanying drawings, forming a part of this specification, in which similar characters of reference indicate corresponding parts in both figures.

Figure 1 is a plan view of a fabric embodying my invention. Fig. 2 is a section on the line 2 2 of Fig. 1.

The fabric comprises warp-threads 1, of

cotton, linen, or other suitable material, and 25 a woof 2, of hog-bristles. The bristles are arranged with the butts or large ends all pointed in the same direction, so that the gradual taper of the bristles will provide for gradual degrees of flexibility transversely of 30 the fabric.

This fabric is particularly adapted for lining shirt-collars; but it will also be found useful for lining cloak and coat collars or other articles where different degrees of stiffness are desired to make the collar or other article set well and retain its shape.

Having thus fully described my invention, I claim as new and desire to secure by Letters Patent—

40 A woven fabric, comprising warp-threads in combination with weft-threads, the latter being bristles, the butts of which all extend in the same direction.

MAUD R. HARTZ.
